[57] CLAIM

The ornamental design for a body jewelry, as shown.

DESCRIPTION

FIG. 1 is a rear perspective view of body jewelry showing my new design;

FIG. 2 is a left side perspective view; and

FIG. 3 is a front perspective view.

The broken line disclosure of a shoulder in FIGS. 1 and 3 is for illustrative purposes only and forms no part of the claimed design.

FIG. 3
